Specification of Letters Patent.

Patented Apr. 23, 1912.

Application filed October 12, 1911. Serial No. 654,380.

To all whom it may concern:

Be it known that I, ORRIN M. SHERMAN, a citizen of the United States, residing at Syracuse, in the county of Onondaga and State of New York, have invented certain new and useful Improvements in Casting Apparatus, of which the following is a specification.

This invention relates to improvements in casting apparatus, designed for use in making metal castings, and the invention relates especially to machines for producing "finished" castings, of the class wherein compressed air is employed for forcing the melted metal into the molds.

The invention relates particularly to an improvement in the casting apparatus shown and described in the Letters Patent of the United States numbered 900,802, 20 900,803, and 924,858, dated respectively October 13, 1908 and June 15, 1909.

The object of the present invention is to provide a casting apparatus of the class, wherein the movable gates formerly employed for cutting off the metal at or near the juncture of the sprue with the mold cavities are entirely eliminated, and wherein the sprue is so arranged that it may be withdrawn from the dies with the castings 30 at the end of each casting operation.

A further object is to provide a casting machine which may be operated by one man instead of two as heretofore.

A further object is to provide a casting machine wherein the general construction, arrangement and operation of the device is such that the "finished" metal castings may be produced more readily, more economically, and with less defects, than similar castings have been produced by the old styles of machines, known to me.

The features and parts of the invention will be understood from the detailed description which follows, and by reference to the accompanying drawings which form a part of this specification, and in which—

Figure 1 is a central vertical longitudinal section, taken on line 1—1 of Fig. 2; showing generally the construction and arrangement of the complete device at the time the casting is done. Fig. 2 is a top plan view of the casting machine taken on line 2—2 of Fig. 1. Fig. 3 is a central vertical longitudinal section, also on line 1—1 of Fig. 2, with certain parts broken away and omitted;

showing the method of parting the dies, for withdrawing the casting from the bottom die-section. Fig. 4 is a similar sectional view; showing the method of stripping the casting from the cores carried by the upper die-section. Fig. 5 is a right side elevation of the device shown in Figs. 4 and 5. Fig. 6 is a top plan view of the lower die-section; showing the mold cavities; also showing means for exhausting the air from the molds before casting. Fig. 7 is a perspective view; showing a group of castings and the sprue, connected as one part, as when ejected from the molds. Fig. 8 is an enlarged view of one of the units of the casting.

In the drawings, 2 represents the top of a table or stand preferably made of iron, which supports the casting mechanism, and which may be mounted by any suitable means.

3 represents a fire-box which is disposed beneath the plate 2, and may be supported in any suitable manner. The top of the fire-box is open and the plate 2 of the table preferably forms the cover for said box during the casting operations. The fire-box may follow any of the well-known constructions, but it is preferably made of wrought or cast metal.

4 represents the melting-pot which is disposed in the fire-box, wherein the metal for making the castings is fused or melted, and 5 represents the discharge spout or nozzle through which the metal is forced for filling the molds. The arrangement of the spout or nozzle 5 is such that its outer or free end contacts closely with the under side of the plate 2 where it coincides with a perforation 6 in the said plate.

Finished metal castings are generally made in molds formed in one or more die-sections, as 7 and 8, which preferably consist of heavy plates or blocks of steel, which are mounted upon the base 2, to which the said sections are securely clamped during the casting operations. The die supporting and clamping frame consists of four like metal guide rods or posts 9, which are disposed vertically, their lower ends made fast in the plate 2, and their upper ends pass through a top clamping plate 10, and then through the arms of a common yoke 10', which is adjustable on said rods by means of a series of nuts 11. The plate 10 is movable vertically on the rods 9 for adjusting the frame for

clamping dies of different size or thickness, and it may be raised and lowered within a certain range by means of a hand-lever 12, which is pivoted by a pin 13 to the yoke, 5 and a link 14 which connects with said lever and said plate.

The lower die-section 7 is preferably rigidly secured to the base 2 of the table by means of screws 15, while the die-section or 10 plate 8 is mounted on top of the section 7, and is detachably secured thereto by means of dowel pins 16, which hold the said sections in proper relations to each other. The upper die-section 8 is preferably rigidly secured to the under side of a head-block 17 15 cured to the under side of a head-block 17 by the dowel pins 16, and the head-block 17 is rigidly secured to the under side of the top plate 10 by screws 17', so that the said parts are movable as one.

20 The molds by which the castings are made, are formed in either one or both of the die-sections 7 and 8, but whenever convenient the molds are usually formed in the lower or fixed die-section, as shown in 25 the drawings. In the present case I have shown a plurality of like molds 18, which are preferably arranged in a circle around a common ingate or sprue, which consists of a cylindrical opening or port 19, which 30 passes downwardly through the lower die-section 7, and communicates and coincides with the perforation 6 in the base 2. The molds 18 are intended to represent any form in which it is desired to cast the metal. 35 Each of the molds 18 is connected with the ingate for the passage of the melted metal by means of shallow runners or gates 20. All of the mold cavities 18 and the 40 runners 20 are preferably formed in or near the top surface of the die-section 7, and face the bottom side of the die-section 8, which in the present device is arranged flat and plain and forms the finished top surfaces of the several castings.

45 The metal from which the castings are made is melted in the pot 4, by a suitable heating agent (not shown) which may be applied to the interior of the fire-box 3 in the usual manner. When the dies are placed 50 in casting position, as shown in Fig. 1, and securely clamped together, as described, the air contained in the molds 18 is exhausted or drawn away, by means of a vacuum pump (not shown) which connects with a 55 pipe 21, which is inserted in a port 22 formed in one side of the die-section 7. The port 22 connects with an annular groove or gutter 23 which is formed in the top surface of the die-section 7 surrounding the 60 several molds 18. Directly opposite each of the molds, the top surface of the section 7 is milled or cut away for forming shallow 65 passages 24 (see Fig. 6) for connecting the mold cavities with the annular groove 23. The die-sections 7 and 8 have their adjacent

surfaces planed off so as to provide an air tight joint between said parts, and when the suction is applied to pipe 21, it draws all the air from the molds 18 and also the ingate 19, and produces a vacuum in said parts. As soon as the air is exhausted from the molds, a pressure is applied to the melting-pot, which generally consists of compressed air, which may be supplied by a pipe A in the usual manner, and by means of which the melted metal is forced from 75 said pot upwardly through the spout 5 and the ingate 19 into the molds 18. The melted metal enters the molds with sufficient force to completely fill all of the said cavities and 80 perfect and compact castings are thus instantaneously formed.

The castings of the present device consist of a series of tubular parts 25, the hollow interiors of which are formed by means of 85 a series of cores, which comprise reduced cylindrical portions 26 formed on the lower ends of rods or shanks 27, which pass through the upper die-section 8. The upper ends of the rods 27 then pass through a 90 core ejecting plate 28, which is disposed in a recess 29 in the head-block 17, directly above and parallel to the top of the section 8, and the said rods are made fast to the 95 said plate by keys 30. When the dies are placed together, as shown in Fig. 1 ready for casting, the lower ends of the cores 26 rest upon the bottoms of the molds 18. After the melted metal has been forced into 100 the molds 18, and has become rigid, the top die-section 8 is detached or moved away from the lower section 7 (see Fig. 4) by means of the hand-lever 12 and link 14, and when the dies are thus parted the castings 105 25 cling to the cores 26, and are thus withdrawn from the molds 18. At the same time the section 8 is parted from the section 7, the sprue or metal 31 which filled the ingate 19 having become rigid or hard like the castings 25, and also the metal 32 110 which filled the gates or runners 20, are all withdrawn from the lower die-section 7 with the castings, as one part; (see Figs. 4, 5, and 7) so that upon the parting of the dies the lower section 7 is rendered entirely 115 clear of all the cast metal.

The withdrawing of the whole of the cast metal in the manner described, is permitted by reason of the funnel-shape of the ingate 19, which is gradually contracted throughout its length from the top to the bottom, as shown in Figs. 1, 4, 5, and 7. After the dies are parted, as shown in Fig. 1, the next operation is the stripping or ejecting of the castings, so as to free them from the die-section 8 and the cores 26. The stripping of the castings is effected by the following parts; 33 represents a pair of like rods, the corresponding sides of which are formed into racks 34, said rods connecting at their 120

lower ends to the core-ejecting plate 28 by keys 35, their upper ends disposed in and guided by sockets or ways 36, arranged vertically in the head-block 17. The rack-rods 5 33 are reciprocated for raising and lowering the plate 28, by means of a common pinion-shaft 37, which is manually operable by means of a hand-crank 38. The rotation of shaft 37 in the proper direction elevates the 10 core-supporting-plate 28, which withdraws the core-rods 27 upwardly through the die-section 8, thus stripping the castings off the cores 26, as shown in Fig. 5. As soon as the castings are stripped and removed the die- 15 section 8 is returned to its casting position upon plate 7 by operating lever 12, after which the core-plate 28 is lowered for inserting the cores 26, in the mold cavities 18 (see Fig. 1), and the machine is ready for 20 another casting operation. The above described operations are repeated for producing each set of castings.

Dies of any suitable size may be employed in connection with the other parts of the 25 apparatus, and molds for making castings of various shapes and forms may be wrought in the dies, without requiring any material changes in the construction and arrangement of the main device, or dies, excepting 30 slight changes in the arrangement and disposition of the cores and runners, may be necessary to suit the different kinds of molds.

The use of the plunger-gates in the past, 35 has always been attended with a number of difficulties, which not only tended to increase the cost of making finished metal castings, but a large percentage of the castings have been imperfectly formed and rendered unfit for use. The plungers being 40 made of steel and arranged to operate in the steel dies, which are constantly heated to a high temperature during the casting operation, the said plungers, owing to their 45 reciprocable playing in the die-sections soon become so worn as to allow air to freely pass into and out of the molds. In order to make perfect castings under pressure it is necessary to exhaust all of the air from the 50 mold cavities just before each filling of the molds, otherwise, the castings will be imperfect. Vacuum pumps, as explained, are usually employed for this purpose, and the said pumps are kept working all the time 55 while the dies are closed or in casting position. When the plunger gates become loosened from the constant wear referred to, the pumps draw air from the outside into the molds, which prevents the forming of a 60 vacuum, and as the melted metal is forced into the molds by a strong pressure, such as compressed air, the sudden inrush of the metal entraps the air in the corners and pockets of the molds, with the result that 65 the castings are imperfectly formed. Fur-

thermore, owing to the rapid wearing out of the mechanical gates, these parts must be replaced with new ones, at short intervals, which again adds to the expense of the output of the machine. The leaking of the 70 air around the worn plungers also tends to weaken the pressure employed for filling the molds, and this renders the castings less compact than if they were made in a 75 vacuum.

Numerous attempts have been made to devise casting machines capable of being operated by one man, and by which finished castings may be produced more cheaply and with less defects and trouble than under the 80 old styles of machines referred to, but none of these, so far as I am aware, have been entirely successful. My improvement is intended to remedy the aforesaid defects and to obviate said troubles, and at the same 85 time produce perfectly formed castings in a ready manner, and at a comparatively small cost. In the present device the essential feature consists of constructing the main ingate 19, in the form of a funnel, 90 wherein the largest end of the ingate is disposed adjacent the mold cavities, while the smallest or reduced end of the said gate is disposed nearest the melting-pot. By this new arrangement, I am able to do away entirely with the plunger gate of the former 95 patents and also the bearing or way in the upper die-section in which the said gate is disposed. By the elimination of these parts, I am able to close up my molds tightly 100 enough to enable the pumps to maintain a vacuum in the mold cavities, which materially aids in the filling of the molds and the forming of perfect castings. Under my new construction, after the molds are filled, 105 it is only necessary to prolong the application of the casting pressure a second or two, for holding the metal in the molds and also in the ingate, long enough to allow the metal 110 to become hard. Then, as soon as the pressure is shut off, the dies may be separated, and the castings and also the sprue are withdrawn from the lower die-section as one part, as shown in Figs. 4, 5, and 8.

By providing the ingate 19, constructed 115 and arranged as herein shown and described, one man is able to turn out as many castings, as the two men, under the old system referred to, and the castings will be more perfectly and evenly formed, and the whole 120 output of the new machines can be produced at a greatly reduced expense.

Having thus described my invention, what I claim as new* and desire to secure by Letters Patent, is—

1. A device for making finished castings, comprising a die-section having a mold cavity formed therein, and having an ingate 125 comprising an upwardly flaring opening formed through the said section, the said 130

- ingate being funnel-shaped, and having its broadest end disposed at the top adjacent to the mold cavity, and its narrowest end disposed in the bottom side of said section, 5 means for forcing the metal upwardly through said ingate for forming a casting and an integral sprue, and means for ejecting the cast metal upwardly without breaking or destroying the casting or sprue.
- 10 2. A casting apparatus, comprising a die, said die having a mold cavity formed in its upper side, an ingate, the said ingate being funnel-shaped, the largest mouth of said ingate disposed at its top end nearest the mold 15 cavity, the smallest mouth of said ingate disposed at the bottom of said die, means for forcing the melted metal through the said ingate into said mold cavity for forming a casting and also a sprue in one integral part, and 20 means comprising a pinion and a pair of racks for withdrawing the said casting and sprue as one part from the said die.
3. The combination of a pair of die-sections mounted one upon the other, the lowermost section having mold cavities formed 25 near its upper side and having a central perforation comprising a funnel-shaped ingate passing downwardly through said section, the broadest end of said ingate disposed at the 30 top of the lowermost die-section nearest the said cavities, and the narrowest end disposed at the bottom of said section, the upper die-section supporting a series of cores arranged to depend into said cavities, adapted to 35 withdraw the castings and also the sprue from the lower section upon the parting of said sections, and means comprising a pinion and a rack for stripping the castings from the said cores.
- 40 4. The combination with a base having an ingate opening and the melting pot disposed beneath the base, said pot having a spout communicating with said opening for the passage of molten metal, of a pair of die- 45 sections supported by said base, one of said die-sections having a mold cavity formed in its upper side and having an ingate comprising a funnel-shaped opening, arranged to coincide with the opening in the base, the said ingate having its largest end disposed 50 in the top of said die-section adjacent the said mold cavity, and having its narrowest end disposed in the bottom of said die-section nearest the said spout adapted to permit the withdrawing of the casting and also the 55 sprue from the lowermost die-section, and a pinion and a pair of racks for lifting the casting and sprue from the lowermost section.
5. A casting apparatus, comprising a table 60 having a perforated base, a pair of dies mounted upon said base, the lowermost die having a mold cavity, the said cavity connecting with the perforation in said base by means of a downwardly extending funnel-shaped ingate, the said ingate disposed so that its largest mouth connects with the mold cavity in the top of the lowermost die while the smallest mouth connects with the perforation in the base, the uppermost die adapted 70 to close the upper side of the mold cavity, a series of reciprocating cores piercing the upper die and depending into said mold cavity, a plate for supporting and operating said cores, said plate disposed above said 75 upper die, means for withdrawing the casting and also the sprue from the lowermost die as one part, a pair of racks connected to said core plate, and a pinion shaft, adapted to operate said racks and said plate for 80 stripping the casting and sprue from said cores.

In testimony whereof I affix my signature in presence of two witnesses.

ORRIN M. SHERMAN.
